UNITED STATES PATENT OFFICE.

JOHN H. NICHOLSON, OF CLEVELAND, OHIO.

MECHANISM FOR MAKING TUBES FROM BILLETS.

SPECIFICATION forming part of Letters Patent No. 628,024, dated July 4, 1899.

Application filed July 18, 1898. Serial No. 686,279. (No model.)

To all whom it may concern:

Be it known that I, JOHN H. NICHOLSON, of Cleveland, in the county of Cuyahoga and State of Ohio, have invented a certain new and useful Improvement in Mechanism for Making Tubes from Billets, of which improvement the following is a specification.

My invention relates to mechanism for making tubes of the general class or type in the operation of which a solid metallic ingot, billet, or blank is passed between the faces of rotating rolls or disks, from which it receives both a rotary and a longitudinal movement and by the action of which it is reduced in diameter and converted into a tube by being forced over a piercing-mandrel in the axial line of the traverse of the ingot, billet, or blank.

The object of my invention is to enable a more powerful endwise motion or feed to be imparted to a billet than has heretofore been practicable and to be so imparted as to tend to obviate the slip on the billet due to the resistance of the piercing-mandrel, said slip as occurring in machines of the class to which my invention relates being objectionable by reason of its tendency to injure the metal.

My invention is also designed to simplify and perfect the construction and operation of mechanism of this class by obviating the necessity heretofore existing for the employment of different sizes of guides for maintaining the billet in a horizontal plane equally distant from the centers of the rolls or disks and enabling a single guide to be used in operating on all billets within the capacity of the machine.

To this end my invention, generally stated, consists in the combination of two rotary members the axes of which are inclined in opposite directions relatively to each of two longitudinal planes which intersect, at right angles one to the other, the axial line of traverse of a billet between the rotary members and which are also inclined in the same direction relatively to one of said planes, but out of line one with the other, so as when produced to intersect said plane on opposite sides of the axial line of the billet or pass, whereby the line of contact of one rotary member with the billet will be wholly above or on one side of the axis thereof and the line of contact of

the other rotary member with the billet will be wholly below or on the other side of the axis thereof.

The improvement claimed is hereinafter fully set forth

The general and characteristic features of machines for making tubes from ingots, billets, or blanks by piercing them while heated and rolling or forcing them into tubular form are well known to those skilled in the art and may be briefly stated as consisting of two or more opposed or overlapping rolls or disks the faces of which are so shaped as to provide a contracting pass or opening between them through which the heated billet is advanced by the rolls over an opposing piercing-mandrel, the billet being rapidly rotated and its diameter reduced by the action of the rolls coincidently with its longitudinal advance or feed. The required rotary and endwise motion has been imparted to the billet by rolls or disks disposed in one or another of the three following ways—to wit, (a) having one or both of their axes intersecting the horizontal plane of the billet or pass; (b) having both their axes in a plane on one side of the horizontal plane of the billet or pass, and (c) having their axes in planes on opposite sides of the horizontal plane of the billet or pass. In each of these dispositions of the rolls or disks the line of contact with the billet is substantially in the horizontal plane of the axis thereof. The billet is advanced and forced down upon and over the piercing-mandrel, against which it abuts, on and around its axial line and around and along which passes the produced cylindrical body of metal which forms the tube.

So far as my knowledge and information extend, no tube-making machine of the class to which my invention relates which has been proposed or put in practice prior to my invention has been provided with a roll or disk which effects the feed of the billet by reason of being disposed in more than one of the three ways which are above specified.

Under my present invention the center of one of the rotary members is raised above and that of the other lowered below a horizontal plane passing through the axis of the billet or pass, so that one of them has its entire length of line of contact with the billet wholly

on one side of said horizontal plane and the other has its entire length of line of contact with the billet wholly on the opposite side of said horizontal plane. The axes of the rotary members are likewise so inclined as, when produced, to intersect longitudinal planes passing at right angles one to the other through the axis of the billet or pass. In such construction the endwise movement or ¹⁰ advance of the billet is due both to the raising and lowering of the centers of the rotary members above and below the horizontal plane passing through the axis of the billet or pass and to the inclination of the axes of the ¹⁵ rotary members to that of the billet or pass in the horizontal plane, which brings the lines of contact of the rotary members with the billet wholly on opposite sides of the horizontal plane.

²⁰ In the accompanying drawings, which illustrate only so much of a mechanism for making tubes as is sufficient to exemplify my invention, Figure 1 is a plan view with the billet partly in section; Fig. 2, an end view as seen ²⁵ from the top of Fig. 1, and Fig. 3 a side view as seen from the left of Fig. 1.

In the practice of my invention I provide two rotary members A and B, which are in the form of rolls or disks and are secured, respectively, upon shafts *a* and *b*, which are mounted in suitable bearings and adapted to be rotated in the directions indicated by the arrows by power-transmission connections to a prime mover. The means for mounting and ³⁵ rotating the shafts *a* and *b* are such as are well known to those skilled in the art and not forming in and of themselves any part of my invention are not illustrated. The faces of the rotary members A and B are each coned ⁴⁰ in the usual manner, so as to form a contracting pass for the longitudinal traverse between them of the billet C from which a tube is to be produced. A piercing-mandrel D, which has a conical head and may be either fixed or ⁴⁵ rotated, is supported in the axial line of the pass or billet, and the billet is rapidly rotated, forced down upon the piercing-mandrel, and advanced longitudinally over the same in the production of the tube by the action of the ⁵⁰ rotary members A and B upon it in the same general manner as in the mechanisms heretofore employed.

The essential and characteristic feature of my invention consists in the angular disposition of the axes *x* and *y* of the rotary members A and B, respectively, relatively to the axis or axial line *z* of the billet or pass, the governing rules of such disposition being as follows: Assuming two longitudinal planes ⁵⁵ at right angles one to the other (as a vertical and a horizontal one) to intersect the axial line *z* of the billet or pass and that said axial line be in a horizontal plane, as is the usual and most convenient practice, the axes *x* and ⁶⁰ *y* of the rotary members are inclined to the vertical plane in opposite directions and at such angles as, in connection with the form

of the faces of the rotary members A and B, will provide a pass of the desired horizontal section between them, as indicated in Fig. 1. ⁷⁰ The axes *x* and *y* are also each inclined in two directions to the horizontal plane—that is to say, viewed in a vertical plane transverse to the axial line *z* of the billet or pass, as indicated in Fig. 2, the axes *x* and *y* of the ⁷⁵ rotary members are each inclined in the same direction and either at the same or at different angles, as preferred, to the horizontal plane, but are not in the same plane or in line one with the other, so that one of said axes (as the axis *x*) when produced intersects the vertical longitudinal plane passing through the axial line *z* of the billet or pass above said axial line, and the other of said axes (as the axis *y*) when produced intersects ⁸⁰ said vertical longitudinal plane below said axial line. When viewed in a longitudinal plane, as indicated in Fig. 3, the axes *x* and *y* of the rotary members are inclined in opposite directions to the horizontal plane, one ⁸⁵ of said axes (as the axis *x*) being downwardly inclined from said plane and the other of said axes (as the axis *y*) being upwardly inclined from said plane. This compound inclination of the axes *x* and *y* might be stated in other ⁹⁰ words as being an inclination in the same direction to a vertical plane with the axes out of line, Fig. 2, and an inclination in opposite directions to a horizontal plane, Fig. 3.

From the above-described relation of the ⁹⁵ axes of the rotary members A and B to that of the pass or billet it follows that the line of contact of one of said members (as the member A) with the billet, one end of which line is indicated at *w* in Fig. 2, will be ¹⁰⁰ wholly above the horizontal plane, and the line of contact of the other member (as the member B) with the billet, one end of which line is indicated at *v* in Fig. 2, will be wholly ¹⁰⁵ below the horizontal plane. The lines of contact of the rotary members with the billet are therefore on opposite sides of each of two planes—a horizontal and a vertical one—intersecting in the axial line of the billet or pass. ¹¹⁰

The application of my invention enables a ¹¹⁵ more powerful action of the rotary members to be exerted in effecting the longitudinal advance or feed of the billet, which is highly desirable and advantageous in the operation of tube-making machines of the class to which my invention relates, and also provides a machine of such construction as promotes its adaptability in practical service for piercing billets of different diameters. It will be obvious to those skilled in the art that if the feed were effected by rolls or disks having their axes in parallel planes, one above and the other below a horizontal plane intersecting the axial line of the pass, means, such as ¹²⁰ the ordinary top and bottom guides, would be required to retain the billet in normal axial line equally distant from the axial planes of the rolls or disks in order that each ¹²⁵

of them may impart to it an equal amount of feed for a given equal angular rotation.

Under my invention two agencies coact in effecting the feed of the billet—to wit, the raising and lowering of the centers of the rotary members above and below the horizontal plane of the pass respectively and the inclination of the axes to the vertical plane of the pass. It is therefore unnecessary to keep the billet in a horizontal plane equally distant from the centers of the rotary members, as the horizontal plane of the pass can be raised or lowered without interfering with the feed, the necessary amount of which for any determined angular rotation being produced by the inclination of the axes of the rotary members after the horizontal plane of the pass midway between the centers of the rotary members has been departed from.

The provision of a plurality of top and bottom guides of different sizes which have been heretofore necessary for holding billets of different sizes in the normal axial line of the pass is obviated by the employment of my invention, in the practice of which a single guide will suffice for all sizes of billets which are within the capacity of the machine. The top member of the guide may also be dispensed with by giving a greater inclination to the axis of one rotary member than to the other. It will be seen that my invention is of decided advantage in operating upon billets of different sizes in avoiding the necessity of the different-sized guides which have been heretofore required in such case.

I claim as my invention and desire to secure by Letters Patent—

1. In mechanism for making tubes from billets, the combination of two rotary members, the axes of which are inclined, in opposite directions, relatively to each of two longitudinal planes, which intersect, at right angles one to the other, the axial line of traverse of

a billet between the rotary members, and which have their centers located, respectively, 45 above and below one of said longitudinal planes, so that their lines of contact with the billet shall be wholly on opposite sides of said plane.

2. In mechanism for making tubes from billets, the combination of a piercing-mandrel, and two rotary members fixed upon shafts which are adapted to rotate on opposite sides of the axial line of said mandrel, the axes of said members being, (a) oppositely inclined to 55 a longitudinal vertical plane passing through said axial line, and themselves intersecting said plane when produced, (b) upwardly and downwardly inclined, respectively, to a horizontal plane passing through said axial line, 60 and themselves intersecting said plane, and (c) inclined in the same direction, out of line one with the other, to said horizontal plane, and with the centers of the rotary members located, respectively, above and below said 65 plane.

3. In mechanism for making tubes from billets, the combination of two rotary members, the axes of which are inclined relatively to planes intersecting the axial line of an intermediate pass or space for the traverse of a billet, in three different directions, to wit; oppositely to said axial line, as seen in plan, upwardly and downwardly relatively to a horizontal plane through said axial line, as seen 75 in side elevation, and in the same direction but out of line one with the other, as seen in end view, and so disposed that the lines of contact of the rotary members, with a billet traversing in said axial line, shall be wholly 80 on opposite sides of each of two planes intersecting in said axial line.
